UNITED STATES PATENT OFFICE.

SAMUEL R. SHOUP, OF WILMINGTON, DELAWARE.

VOTING-MACHINE.

No. 852,911.

Specification of Letters Patent.

Patented May 7, 1907.

Application filed February 8, 1905. Serial No. 244,775.

To all whom it may concern:

Be it known that I, SAMUEL R. SHOUP, a citizen of the United States, residing in Wilmington, Delaware, have invented certain 5 Improvements in Voting-Machines, of which the following is a specification.

My invention relates to voting machines and consists of certain improvements in that class of mechanical counting mechanism 10 whereby I am enabled to reduce the number of operating parts, facilitate the operation of voting, enable a person to vote a "straight" or "cut" ticket, and "yea" or "nay" on special questions, and at the same time provide means to prevent fraudulent voting of any kind whatsoever; the mechanism being so arranged that the operation of that part necessary to cast a vote in whole or part locks and prevents the movement of similar 15 mechanism for further voting until reset by the election officers.

My invention is fully shown in the accompanying drawings, in which:

Figure 1, is a front elevation of my improved 20 voting machine, partly broken away, and partly in section on the line *a—a*, Fig. 2; Fig. 2, is a sectional plan view of the same, taken on the line *b—b*, Fig. 1; Fig. 3, is a cross-sectional view of part of the machine, taken on 25 the line *c—c*, Fig. 2; Fig. 4, is a perspective view of detached parts forming the elements 30 of the operating structure; Fig. 5, is an enlarged view of a portion of the operating structure and the counting mechanism operated therefrom; Fig. 6, is a sectional view of 35 an independent ballot-box for use in connection with my voting machine; Fig. 7, is a sectional view of the ballot-box, taken on the line *d—d*, Fig. 6, and Fig. 8, is a view of a 40 series of diagrams illustrating the operation of parts of the mechanism.

In the drawings, 1, 2, 3 and 4 represent 45 series of knobs or handles to be turned by the voter for the purpose of registering a vote, and these knobs or handles in the present instance are arranged in several series; the main set comprising six vertical rows of six knobs or handles each, another set comprising two knobs or handles 5 and 6 for the 50 "yea" and "nay" vote on special questions, and another set comprising three knobs or handles 2^a, 3^a and 4^a for independent ballot boxes.

The knobs or handles 1 of the upper row

are arranged to vote what is termed a 55 "straight ticket." In practice there will be as many operative knobs or handles as there are parties, and each knob is to be turned a half revolution for the purpose of registering a single vote. In like manner, the knobs 2, 60 3, 4, are to be turned for registering a vote, but unlike the upper row they serve for sectional parts of each ticket only; the knobs 5 and 6 are to be used to vote "yea" or 65 "nay;" while the knobs 2^a, 3^a and 4^a, are to be turned to enter a specially prepared ballot. As an instance of one form or arrangement of voting, the knobs or handles 2 may 70 actuate mechanism for registering votes for the electors of the several presidential tickets; the knobs or handles 3 may be arranged to actuate mechanism registering votes for judges or other nominees on the several tickets; and the knobs or handles 4, as arranged herein, are for voting for two or more candidates, as the case may be, when two or more candidates are to be chosen on a single ticket; as, for instance, when councilmen, 75 trustees or other municipal officers of a similar character are to be voted for. The knobs 80 5 and 6 are to be used for voting "yea" or "nay," and the mechanism controlled thereby is precisely similar to the mechanism of the other handles or knobs.

Carried by the spindles 10, 11, 12 and 13, 85 of the knobs or handles 1, 2, 3 and 4, respectively, are a series of segmental pinions 14, 15 and 16, and the notched wheel 17. The wheel 17 is provided with two notches which engage at certain intervals with a long tooth 90 of a pinion 18 mounted on an independent spindle 19, of which there is one for each of the spindles of the knobs or handles of the apparatus, said pinion 18 having a set of long teeth 18^a for such engagement and a set 95 of short teeth 18^b, which, with the long teeth 18^a, mesh with a unit wheel 20 of counting mechanism arranged adjacent to or on the spindles carrying the actuating knobs or handles. These spindles 19 carry other pinions 21 and 22, arranged to mesh with and operate wheels 23 and 24 of the counting mechanism employed for registering the number of votes cast, and in the present instance the counting mechanism is carried by the spindles 10, 11, 12 and 13. This counting mechanism is similar to that shown and described in my Patent No. 694,682, dated

March 4, 1902, and excepting in its special adaptation and arrangement with the other mechanism, it forms no part of my present invention.

3 The pinions 14, 15 and 16 I have termed segmental pinions, as they are each provided with two sets of two teeth 25, arranged on the periphery of the same at diametrically opposite points, and these teeth are adapted 10 to engage slidable bars 26, 27 and 28 suitably mounted in ways 29 carried by the front plate of the machine. These bars are provided with separated rack portions comprising recesses 30 arranged in sets of two, and forming 15 between them a single tooth 31 for engagement with the teeth of said segmental pinions. These segmental pinions are mounted on their respective spindles in various positions so that the teeth carried there- 20 by are disposed at various points with relation to the teeth of the other pinions, but the recesses in the bars with which these teeth engage are arranged in line so that while any one of said pinions may engage one of said 25 bars, its time of engagement may differ from the engagement of all the other pinions with said bars. These bars are moved by giving any one of the respective operating knobs or handles a full half turn, and the actual en- 30 gagement of the pinions with said bars will vary within certain limits depending upon the position of the teeth of the pinions arranged to engage such special set of bars. When one of said sets of bars has been suc- 35 cessively moved by such engagement it will be impossible to move another bar, or, in fact, to move any of the handles or knobs on the same row as such movement has displaced the other teeth of the bars with respect to the segmental pinions.

40 The purpose of having a number of pinions and a number of bars, three in each case, is to provide for various combinations of the co-acting parts each of which after being actuated 45 and causing the registration of such actuation will lock the rest of the knobs or handles on the respective or particular rows. For instance, the first spindle of the first row will have its pinion 14 so disposed that the teeth 50 of the same will engage the recesses in the slidable bar 26 and upon giving such knob or handle a full half turn, said bar will be moved to the left the full distance provided for to lock certain mechanism to be fully described 55 hereinafter for preventing the turning of the other knobs or handles. In the case of the knobs or handles of the same row, the movement of the sliding bar will displace the other sets of recesses and teeth, bringing the 60 plain sections of said bars opposite the teeth of the other segmental pinions 14, and thereby preventing the engagement of such teeth with the same. At the same time and in proper sequence as the movement of the 65 handle continues, the other bars 27 and 28

will be moved by the engagement of the pinions 15 and 16 therewith, said pinions being mounted on the spindle of the knob turned; such engagement following that of the pinion 14 and moving said bars 27 and 28 the necessary distance which also brings the plain sections of said bars opposite the point where the teeth of the pinions of the other knobs or handles of the same row would engage.

70 In diagram, Fig. 8, I have illustrated the movement of the bars by the engagement of the several pinions. To lock these bars after they have been moved and prevent the registration of another vote on the same row, as such movement is designed to operate the counting mechanism one unit, I provide pawls 35 adapted to engage notches 36 in said bars after they have been moved. These pawls are carried by a vertically movable bar 37, which is to be raised by the election 80 officers when it is desired to reset the horizontally slidable bars 36, 37 and 38, after a voter has left the booth containing the voting machine. In addition, I employ a cam bar 85 38 mounted adjacent to the pawl carrying bar and having cams 39, into the spaces between which the horizontal sliding bars may be moved. These cams have angular faces 40, and the sliding bars are also beveled at 41 so that after they have engaged said cams, 90 which means that they have been moved the proper distance which is also sufficient to prevent the lifting of said cam bar 38, they may be readily retracted by lowering said bar.

95 The sliding bars controlling the straight ticket, instead of passing into the spaces between the cams 39 of the bar 38 engage an upper cam 42 carried by the same, and when such bars are given lateral movement by the 100 operation of the knobs or handles, they raise said cam bar, and said slidable bars being held by the pawls 35, such cam bar will be maintained in the raised position which brings a series of guards 43 adjacent to the 105 other cams in line with the other sets of slid- 110 able bars, thereby preventing movement of the same, so that when a person votes a "straight" ticket of any one of the political parties, it will be impossible to vote any sec- 115 tional part of any other ticket.

120 As it is always necessary to provide means for enabling voters desiring to make up their own ticket to properly cast the same, I mount a series of ballot boxes 45 upon the face plate of the machine to the right of the same. These ballot boxes are provided with brackets 46 on their rear to engage the ribs 47 carried by said face plate whereby they 125 may be supported in place. They are operated by knobs 2^a, 3^a and 4^a, similar in all respects to those employed for registering the other votes, being operated in the same manner and moving a series of bars to lock the other knobs or handles on the same row 130

I prefer to have cards of definite size and thickness for the purpose of making these independent votes, which will be entered in a manner to be described, and it will be understood that after using a ballot and operating the ballot box, it will be impossible to actuate any other knob or handle on the same row.

Each ballot box is provided with a rotatable member 50 carried by the spindle of its knob or handle, which member is locked against movement by a loose pawl 51 which is arranged to be displaced by the ballot when the latter is inserted through the slot 52 of the ballot box casing. A flange 53 is carried by the rotating member and as the rotating member is to be turned a full half turn, I provide the same with a pair of slots 54 so that every time said rotating member is turned a full half revolution, one of said slots will be brought into registry with the slot 52 of the casing and in position to receive a ballot.

The ballot rests on the narrow edge or side of the rotatable member, and as soon as the knob or handle is turned, said ballot falls off into the box. In order to bring said member into position to receive another ballot, the knob or handle must be given a full half turn, but as the ballot may be deposited without making such full half turn, in order to prevent the backward movement of the knob or handle of the ballot box, a ratchet wheel 55 is carried by the spindle with which a pawl 56 engages. In case one voter does not give such knob or handle a full half turn, the next voter desiring to use the box must finish the movement so as to bring the slots in registry to receive another ballot.

The spindle of this rotating member will carry the pinions and wheel, 14, 15, 16 and 17, in operative engagement with a set of slideable bars 26, 27 and 28, and the counting mechanism already described, so that when the ballot box knob is turned the sliding bars will engage the cam bar and prevent the voting of a straight ticket in addition to the deposit of a special ballot, as well as the voting of any sectional part of the ticket on the same line of knobs as the ballot box.

The lower series of knobs or handles in the present embodiment of my invention carry four segmentally toothed disks, the additional one being indicated at 57, each of which controls an independent laterally slideable bar. This arrangement is to permit the voting for several candidates in such cases where two or more from a number are to be selected, as for instance, when, as often happens in small towns, a number of councilmen or school directors are nominated, two or three of whom only are to be elected. In this case, each candidate will have an independent knob and the segmentally toothed gears carried by said knobs and the laterally sliding bars having recesses for engagement

by these wheels, will be set so as to permit the operation of one, two or three of said knobs or handles, whereby votes may be cast for one, two or three of the candidates, as the case may be.

Below the regular sets or series of knobs or handles for voting the ticket in whole or part, two knobs or handles 5 and 6 are arranged by which the "yea" and "nay" vote may be taken. These knobs have spindles carrying segmental gears for operating the slideable bars the same as the other knobs and spindles. The bars in this instance, however, are shorter than the others, and they engage the cam bar in the same manner.

In Fig. 8, I have illustrated the manner in which the slideable bars are moved. A represents the bars at rest in the retracted position; B shows slideable bar 26 partially moved toward the cam bar 38, representing the first part of the movement of one of the knobs or handles; C shows slideable bar 26 fully moved and bar 27 partially moved; D shows slideable bars 26 and 27 fully moved and bar 28 partially moved, and E shows bars 26, 27 and 28 fully moved into engagement with the cam bar 38, a result accomplished by the engagement of the teeth of the segmental pinions 14, 15 and 16, with the racks of the slideable bars, upon giving one of the knobs or handles the full half turn as required to register a vote. After each voter has finished manipulating the machine for the purpose of casting the vote he desires to make, it will be necessary to shift or reset the slideable bars and all of the mechanism controlled by or controlling the same, excepting the counting or registering mechanism, which, of course, retains the position in which it has been placed by the previous voter.

For the purpose of operating this shifting mechanism, I provide the slideable rod 60, which carries the links 61 and 62, the former being connected to the pawl carrying bar 37, while the latter is connected to the cam carrying bar 38. The link 62 is slotted at 63 and a pin 64 carried by the cam bar is disposed in said slot. This arrangement provides for independent vertical movement of the cam carrying bar, such movement being imparted when the upper set of the slideable bars are moved. The slideable rod 60 is under control of the election officers, and movement of the same except as they desire, is prevented by the bolt 65 engaging a notch 66 in the same. When this bolt is lifted, the rod 60 may be operated, and this operation will accomplish two things: it will raise the pawl carrying bar, releasing the slideable bars, and it will then lower the cam carrying bar so as to retract the slideable bars, the latter being engaged by the cams of said bar as the latter is lowered. This bar 60 may be connected in any suitable manner with a lever or other controlling means adjacent to the proper election offi-

cer, or it may be combined with the door leading to the booth so that when a voter leaves the booth the action of opening or closing the door, or booth, will reset the slide-
5 able bars.

For the purpose of providing for the reset-
10 ting of the counting wheels after the entire
vote has been cast and it is desired to prepare
the machine for another election or for fur-
15 ther use, the spindles carrying the pinions
for operating the registering pile are support-
ed by a slideable frame formed of the bars 70
and 71 suitably mounted so as to slide, and
20 connected together and spaced apart by the
spindles 19, which are normally in a position
to bring said pinions into proper engagement
with the counting wheels; the bars of which
25 frames are slotted at 70^a and 71^a, respectively,
adjacent the spindles 10, 11, 12 and
30 13, whereby they may be moved laterally to
withdraw said pinions from such engagement
and permit the wheels of the registering pile
to be turned to the zero point. These frames
35 are supported at the ends by the projecting
arms 72 and a bar 73 is employed to lock
them with the pinions on the spindles 19 in
the operative position. This bar is notched
40 at 74 so that when unlocked and partially
raised any one or all of the frames carrying
said spindles 19 may be moved.

My improved mechanism is based upon a
unit system, and is so constructed and ar-
ranged that a frame carrying a series of
45 knobs and the necessary mechanism can be
added to the machine as desired, it only be-
ing necessary to correspondingly lengthen
the cam bar, the pawl carrying bar, and the
bolts or other means for fastening the ma-
50 chine together. The machine is arranged to
be accessible from one end or the other to
reset the numbering or counting mechanism
after the voting has finished, and at the back
of the machine, I provide a door 75 of iron or
55 other material which covers a glass door 76
through which the numbering mechanism
may be viewed and the number of votes to-
taled without opening the machine, although
said glass door is also provided with a lock
60 and hinges so that access to the interior of
the casing may be gained by the proper au-
thorities.

Having thus described my invention, I
claim and desire to secure by Letters Patent:

1. The combination, in a voting machine,
of a casing, a series of independent counting
mechanisms mounted within said casing,
means for independently operating each of
65 said counting mechanisms, rotatable mem-
bers controlling the actuation of said means,
a series of sets of slideable members, engaging
means carried thereby, and means carried by
the rotatable members for moving said slide-
70 able members, the arrangement of the engag-
ing means of each rotatable member differing
from all the others, and the relation of the

parts being such that when one of the rota-
table members is operated to move a set of
the slideable members the rest of said rota-
table members will be locked against opera-
75 tion.

2. The combination, in a voting machine,
of a casing, a series of independent counting
mechanisms mounted within said casing,
means for independently operating each of
80 said counting mechanisms, a series of sets of
slideable members, engaging means carried
thereby, rotatable members controlling the
means for operating the counting mechan-
isms, said members having means arranged
85 to operate during their actuation of the
counting mechanism and move one of said
sets of slideable members, the engaging means
of the latter coacting therewith, the arrange-
ment of the engaging means of each rotatable
90 member differing from all the others, and the
relation of the parts being such that when
one of the rotatable members is operated to
move a set of the slideable members the rest of
said rotatable members will be locked against
95 operation.

3. The combination, in a voting machine,
of a plurality of sets of horizontally slide-
100 able bars having engaging means, a series of rota-
table members, means for coaction there-
with, to move any set of said bars, carried by
said rotatable members, the arrangement of
the engaging means of each rotatable mem-
105 ber differing from all the others, and the rela-
tion of the parts being such that when one of
the rotatable members is operated to actuate
a set of the slideable bars the rest of said rota-
table members will be thereby locked against
110 operation, vertically moving means for re-
leasing said bars, and means for retracting
said bars immediately following their release.

4. The combination, in a voting machine,
of a set of slideable bars, a rotatable spindle,
115 a plurality of means one for each bar carried
by said spindle for coaction with said bars to
move the same; counting or registering mech-
anisms, and means for actuating the same
also carried by said spindle, said counting or
120 registering mechanisms being operated dur-
ing the movement of said spindle necessary
to move the bars.

5. The combination in a voting machine,
of a plurality of sets of slideable bars, a series
125 of rotatable spindles, a plurality of means
carried by said spindles one for each bar car-
ried by said spindles for coaction with said
bars to move the same, sets of independently
operable registering or counting mechanisms,
and means for actuating the same also car-
ried by said spindles, the arrangement of the
engaging parts of each spindle differing from
130 all the others, and the relation of the parts
being such that when one of said spindles is
operated to actuate a set of the slideable bars
the rest of said spindles will be thereby
locked against operation, one of the register-

- ing or counting mechanisms being operated during the rotation of any one of said spindles necessary to move one of said sets of bars.
6. The combination in a voting machine, 5 of the slidable bars, a spindle, means carried by the spindle for moving said bars, and counting or registering wheels mounted on said spindle.
7. The combination in a voting machine, 10 of a series of slidable bars, a series of spindles, means carried by the spindles for moving said bars, and independent sets of counting or registering wheels mounted on said spindles.
- 15 8. The combination in a voting machine, of the slidable bars, a spindle, means carried by the spindle for moving said bars, counting and registering wheels mounted adjacent to said spindle, and pinions actuated from said 20 spindles for moving said counting or registering wheels.
9. The combination in a voting machine, 25 of the slidable bars, a spindle, segmental gears carried by the spindle for moving said bars, counting and registering wheels mounted adjacent to said spindle, pinions for moving said counting or registering wheels, and means actuated from said spindle for operating said pinions.
- 30 10. The combination in a voting machine, of a spindle, a segmental gear carried thereby, counting wheels operated from said spindle, a pinion for actuating the unit wheel of said counting mechanism, and means carried 35 by the spindle and brought into operative position at every half turn of the same for actuating said pinion.
11. The combination in a voting machine, 40 of a spindle, a segmental gear carried thereby, by, counting wheels mounted on said spindle, a pinion for actuating the unit wheel of said counting mechanism, and a wheel recessed at diametrically opposite points and carried by the spindle for actuating said pinion at every half turn of said spindle.
- 45 12. The combination in a voting machine, of a spindle, a slidable bar, a slotted bar engaged thereby, means carried by said spindle for actuating said slidable bar, and means 50 for registering the movement of said spindle simultaneously with the movement of the slidable bar.
- 55 13. The combination in a voting machine, of a spindle, a slidable bar, a slotted bar engaged thereby, means carried by said spindle for actuating said slidable bar, and a series of 60 counting or registering wheels loose on said spindle and actuated simultaneously with the movement of the slidable bar to register 65 the movement of the spindle.
14. The combination in a voting machine, 65 of a casing, a series of slidable bars mounted therein, segmental pinions arranged to engage said slidable bars, spindles for carrying and turning said pinions, registering and 70 counting mechanism combined therewith, and means operatively connecting said mechanism and the spindles.
15. The combination in a voting machine, 75 of a casing, a series of sliding bars mounted therein, segmental pinions arranged to engage said sliding bars, means for turning said pinions, and registering and counting mechanism combined therewith.
16. The combination in a voting machine, 80 of horizontally slidable bars, a spindle, segmental pinions carried by said spindle and arranged to move said bars, a pile of counting or registering wheels also carried by said spindle, independently mounted pinions for 85 operating said counting or registering wheels, and means for bodily shifting said pinions in a horizontal plane whereby said registering pile may be reset.
17. The combination in a voting machine, 90 of horizontally sliding bars, a spindle, segmental pinions carried by said spindle and arranged to move said bars, a pile of registering wheels also carried by said spindles, pinions for operating said registering wheels, 95 and means for bodily shifting said pinions in a horizontal plane whereby said registering pile may be reset.
18. The combination in a voting machine, 100 of a series of spindles, counting wheels mounted on said spindles, a series of pinions for actuating said counting wheels, shafts or spindles carrying said pinions, and a frame in which said pinion spindles are mounted, said frame being laterally movable in a horizontal plane to withdraw them from engagement with the counting wheels whereby the latter may be reset to the unit position.
19. The combination in a voting machine, 105 of a series of sliding bars, a spindle, pinions carried by said spindles and arranged to move said sliding bars, a registering pile of gears carried by said spindle, an independent spindle, pinions carried thereby for operating the registering pile, and a frame arranged to 110 slide in a horizontal plane in which said pinion spindles are mounted whereby said pinions may be removed from engagement with the registering pile to permit the resetting of the same.
- 115 20. The combination in a voting machine, 120 of a series of sets of slidable bars, a series of spindles, pinions carried by said spindles and arranged to move said slidable bars, a registering pile of gears carried by said spindle, an independent spindle, pinions carried thereby for operating the registering pile, a sliding frame in which said pinion spindles are mounted whereby said pinions may be removed from engagement with the registering 125 pile to permit the resetting of the same, the bars of said frame being slotted for such movement.
21. The combination in a voting machine, 130 of a series of spindles, counting wheels mount-

ed on said spindles, a series of pinions for actuating said counting wheels, shafts or spindles carrying said pinions, a frame in which said pinion spindles are mounted, said frame being laterally movable in a horizontal plane to withdraw them from engagement with the counting wheels whereby the latter may be reset to the unit position, and means for locking said frame, said frame embracing the main spindles and being slotted adjacent thereto for lateral movement.

22. The combination in a voting machine,

of counting mechanism, actuating pinions for said counting mechanism, a frame mounted to slide in a horizontal plane for supporting said pinions, and a lock for holding said frame against movement.

In testimony whereof, I have signed my name to this specification, in the presence of two subscribing witnesses.

SAMUEL R. SHOUP.
